Attest.

mally passes said perforated plate to the burner chamber through said tubes and sudden gusts of air escape through said openings.

2. A lantern comprising, a burner chamber, a chimney head, means for supporting said chimney head above said burner chamber comprising tubes communicating the burner chamber with the head, a conical rim carried by the lower

portion of said head, said rim having openings arranged in the flaring skirt thereof whereby air normally passes through the rim to the burner chamber by means of said tubes and sudden gusts of air escape through the openings arranged in the flaring skirt of said rim. 5

Y
BRUNO NIER.
